UNITED STATES PATENT OFFICE.

EDWARD WILLIAMS, OF LYNN, MASSACHUSETTS.

OIL-DISTRIBUTING APPARATUS.

SPECIFICATION forming part of Letters Patent No. 434,968, dated August 26, 1890.

Application filed November 15, 1889. Serial No. 330,346. (No model.)

To all whom it may concern:

Be it known that I, EDWARD WILLIAMS, a citizen of the United States, residing at Lynn, in the county of Essex and Commonwealth of 5 Massachusetts, have invented a new and useful Oil-Distributing Apparatus, of which the following is a specification.

My invention relates to improvements in oil-distributing apparatus in which a flexible 10 bag, perforated at one end, contains the oil, which is forced out through said perforations in proper quantities by contraction of said bag.

The object of my invention is to produce a 15 flexible apparatus more perfectly protected from injury than any apparatus of that class heretofore used and in which the flow of oil is more directly under control of person using same.

20 The accompanying drawings are illustrations of my invention.

Figure 1 is a side view of the entire apparatus. Fig. 2 shows the arrangement of cords used in connection therewith. Fig. 3 is a side 25 view of the apparatus when empty. Fig. 4 is a side elevation of the device for perforations.

Similar letters refer to similar parts throughout the several views.

30 S represents the flexible bag containing the oil, the end A of said bag being perforated and the end B having an aperture through which the bag may be filled.

X and Y are the cords or lines used to contract the bag S. They pass freely through 35 the loops or rings d and e, cross each other at or near the center of the bag, and are fastened to the cord h. They then pass freely through the loops or rings f and g. The arrangement

40 of cords X, Y, and h on the other side of bag S is similar to that just described. (See Fig. 2.) The cords X and Y are again passed through the loops or rings d and e, each crossing itself at these points, respectively, and

45 the ends are fastened to the suspending-rope D. The ropes or cords l, m, n, and o pass entirely around the bag S, being held in place by rings or loops secured thereto. They are used in connection with cords X, Y, and h to

50 relieve bag S from the strain resulting from weight of oil and other parts of apparatus,

and by forming a net-work to protect bag S from injury.

When the apparatus is filled with oil and thrown into the water for use, any sudden 55 pull on rope D, the weight of oil and other parts of apparatus and resistance of water opposing, will draw the cords X and Y through the loops or rings d and e and so contract bag S, forcing out the oil through the perforations at A. The cords X and Y, being crossed as they pass through d and e, will hold bag S in its contracted form as long as there is any strain on these cords resulting from weight of oil and other parts of apparatus. 60 The action of waves and lurching of boat or vessel will in many cases be sufficient to draw up cords X and Y, and so force out the oil from bag S in sufficient quantities. The bag S may be so contracted until all the 65 oil is forced out, and bag brought into form shown in Fig. 3. The bag S may be made of impervious material and kept full of oil and ready for use.

I use the following device for perforations 70 and for closing same at end A of the bag S. A tube T, having one end closed by a perforated metallic disk, is passed through an aperture in the end of the bag, the tube fitting tightly in the aperture and disk being 75 on inside of bag. The portion of tube outside of the bag is threaded, so as to turn into another metallic disk, the material of bag being thus firmly held between the two disks and tube T kept in place. The end of tube 80 T is provided with a cap, by which it may be closed when it is desired to retain oil in bag S.

I claim as my invention and desire to secure by Letters Patent—

The combination, in an oil-distributing apparatus, of a flexible bag perforated at one end and having a device for closing said perforations, and a system of cords connected with a suspending-rope passing around said bag and each crossing itself through a ring 90 or loop attached to the top thereof, said cords acting to contract said bag and retain it as contracted, substantially as set forth.

EDWARD WILLIAMS.
